United States Patent Office.

ROBERT ASHE, OF SOMERVILLE, MASSACHUSETTS, ASSIGNOR TO HIMSELF
AND GEORGE W. ELDREDGE.

Letters Patent No. 67,158, dated July 23, 1867.

IMPROVED BABY-JUMPER AND CRADLE.

The Schedule referred to in these Letters Patent and making part of the same.

TO ALL WHOM IT MAY CONCERN:

Be it known that I, ROBERT ASHE, of Somerville, in the county of Middlesex, and State of Massachusetts, have invented a Combined Baby-Jumper and Cradle, of which the following is a full, clear, and exact description, reference being had to the accompanying drawings, making part of this specification, in which—

Figure 1 is a perspective view of my improved baby-jumper and cradle combined.

Figure 2 is an elevation of one side of the same, a portion of the cradle being removed so as to form a chair.

Figure 3 is a perspective view of the front portion of the cradle detached.

In the apparatus for which Letters Patent of the United States were granted to T. P. Thorpe, on the 10th of April, 1866, the seat was supported on rods which were brought together near the end of the base and formed into coiled springs which were attached thereto. With this arrangement, if the child should lean over to one side the rods will twist at the point where they are brought together and allow the seat to tip sidewise to such an extent that the child will fall out on to the floor. Another objection is that the springs cannot be adjusted for children of different weight.

To overcome these difficulties is the object of my invention, which consists in securing the rods which support the cradle or seat to the base at such a distance apart as to prevent the cradle or seat from being tipped laterally; the ends of the rods being bent to form springs which slide on the base or in projections rising therefrom, so that the strength and resistance of the springs may be varied to correspond with the weight of the child who is to occupy the cradle or seat. And my invention also consists in making a portion of the cradle removable, so that the remaining portion will form a seat or chair.

To enable others skilled in the art to understand and use my invention, I will proceed to describe the manner in which I have carried it out.

In the said drawings, A is the base, which is made of cast iron or other suitable material of sufficient weight. B is a cradle, which is supported on rods C, which allow it to be vibrated in the arc of a circle. These rods, which extend down in a line parallel with the sides of the cradle throughout their whole length, are so bent at their ends (which are of steel properly tempered) as to form springs a, which slide through staples b, projecting from the base A, by which means they are held securely in place. Instead of the springs sliding beneath staples, as shown, they may be fitted to slide in guides, and be held in place by set-screws or otherwise, as may be preferred. By sliding the straight portions of the springs through the staples b towards or from the front edge of the base A, their strength and power of resistance may be diminished or increased to correspond with the weight of the child who is to occupy the cradle. And it will be seen that the springs a of the rods C being attached to the base at a considerable distance apart, instead of being brought together as in the aforesaid patent of T. P. Thorpe, it will be impossible for them to twist to allow the cradle to tip sidewise sufficiently for the child to fall out, no matter how much it may lean to one side or the other. The cradle B is made in two portions, 4 and 5, the front portion (5) being provided with hooks c, which fit into sockets d, projecting from the inside of the rear portion 4; the front end of the portion 5 being supported by projections e, (one on each side,) which hook over the rods C. The front portion of the cradle may thus be readily removed, when the rear portion 4 will form a seat or chair, as seen in fig. 2.

One of the advantages resulting from attaching the rods C to the base at a considerable distance apart is, that when the front portion of the cradle is removed the child can walk up between the rods to the seat 4, while it requires to be lifted in when the rods are brought together, as in the aforesaid patent of T. P. Thorpe.

By thus making the springs a adjustable at their lower ends, the seat or cradle will always swing in the arc of a circle of the same diameter, thus giving it the same amount of motion, while if the seat is made to slide on the rod or rods, the nearer it is moved towards the point where the springs are attached to the base, the less will be its motion, as it will vibrate in the arc of a smaller circle. If desired, an elastic cord may be attached to the base A and to the portion 4 of the cradle to regulate its motion and prevent it from being thrown up too high by the springs a.

Claim.

What I claim as my invention, and desire to secure by Letters Patent, is—

The combination of the base A, the seat or cradle B, and the rods C, with their springs α , when the latter are arranged and secured at such a distance apart as to prevent the seat or cradle from tipping to one side, substantially as set forth.

I also claim, in combination with the above, making the springs α adjustable, so that they can be advanced or withdrawn in order to increase or diminish their power of resistance, substantially as described for the purpose set forth.

I also claim making the front portion 5 of the cradle removable, so that the remaining portion may be used as a chair or seat, substantially as set forth.

ROBERT ASHE.
